UNITED STATES PATENT OFFICE.

CHARLES P. H. NASON, OF PHILADELPHIA, PENNSYLVANIA.

DESIGN FOR A BANNER.

SPECIFICATION forming part of Design No. 24,261, dated April 30, 1895.

Application filed March 30, 1895. Serial No. 543,904. Term of patent 7 years.

To all whom it may concern:

Be it known that I, CHARLES P. H. NASON, a citizen of the United States, residing at Germantown, (Philadelphia,) in the county of 5 Philadelphia and State of Pennsylvania, have invented and produced a certain new and original Design for a Banner, of which the following is a specification.

The leading feature of my design consists 10 of a banner having flaring projecting points and with the surface ornamentation of a crusader's cross, typifying the great sacrifice made for human redemption, a trefoil disposed about the center of the cross, typifying 15 the Trinity, and inclosing a paschal lamb, bearing by extended limb a cross, typifying childhood and the Passover.

Referring to the accompanying drawings, 20 Figure 1 is a front elevational view of a banner with the surface ornamentation displayed thereon embodying the features of my design; and Fig. 2 is a cross-sectional view through the banner on the line α α' of Fig. 1, illustrating the surface ornamentation thereof.

25 Referring to the drawings A, is the ground of the banner tapering from one end to the other and terminating in flaring projecting points a and a' .

B, is a crusader's cross typifying the great sacrifice made for human redemption. 30

C, is a trefoil, occupying a position about the center of the cross and typifying the Trinity.

D, is a paschal lamb inclosed within the trefoil, which lamb is represented with one of 35 the front limbs c , extended bearing a cross d , typifying childhood and the Passover.

The ground A, of the banner is of cloth or other material borne by a cross-bar suitably attached to a staff and the design or surface 40 ornamentation of the banner with its color effects and symbolism is applied to the said ground A, so as to appear in bold relief as shown.

What I claim as my invention, and desire 45 to secure by Letters Patent, is—

The design for a banner substantially as illustrated and described.

In testimony whereof I have hereunto set my signature in the presence of two subscribing witnesses. 50

CHARLES P. H. NASON.
